UNITED STATES PATENT OFFICE.

JOHN G. CLEMENS, OF BUFFALO, NEW YORK.

TOY.

1,204,132.

Specification of Letters Patent.

Patented Nov. 7, 1916.

Application filed March 22, 1916. Serial No. 86,026.

To all whom it may concern:

Be it known that I, JOHN G. CLEMENS, a citizen of the United States, residing at Buffalo, in the county of Erie and State of New York, have invented certain new and useful Improvements in Toys, of which the following is a specification.

This invention relates to toys and has as its object to provide a toy which will afford considerable amusement and which may be manufactured and sold at a low cost. The toy is of that type resembling the well known "Cartesian diver" and it is one aim of the present invention to so construct the submergible image as to insure of same rising to the surface of the water when the pressure creating device is rendered inactive so that it will not be necessary to repeatedly empty the water from the tube for the purpose of removing any surplus volume of water which may have remained within the image after having been submerged.

In the accompanying drawings: Figure 1 is a view partly in side elevation and partly in vertical section illustrating the toy embodying the present invention, the submergible image being illustrated in section and at the surface of the liquid within the tube or body of the toy. Fig. 2 is a vertical longitudinal sectional view through the toy, the image being illustrated submerged. Fig. 3 is a detail view partly in side elevation and partly in longitudinal section, illustrating the said submergible image.

In the drawings the toy is illustrated as including a base 1 which may be of wood, papier mâché or any other suitable material and which is provided in its upper side with a socket 2 receiving the lower end of a glass tube 3, this end of the tube being closed and its upper end being open, as clearly shown in Figs. 1 and 2 of the drawings. At its upper end the tube is provided exteriorly with a bead 4 which surrounds the mouth of the tube and fitted to the said mouth of the tube is a rubber bulb 5 preferably having a thickened rim 6 fitting beneath the bead 4 and snugly surrounding the tube immediately below the said bead whereby to render the connection between the bulb and the upper end of the tube an air-tight one. The tube 3 is nearly filled with water as indicated at 7 and placed within the tube and upon the surface of the water is the sub-

mergible image shown clearly in Fig. 3 of 55 the drawings. This image comprises a hollow body 8 which in shape preferably resembles a submarine and the body preferably is formed with a hollow turret portion 9. The body is closed on all sides except at its 60 bottom where it is provided with an opening 10 and the said bottom of the body is formed interiorly with a flange or wall 11 which surrounds the opening 10 and extends upwardly into the body with its upper edge 65 terminating in a plane substantially at the longitudinal median line of the body. By reference to Fig. 1 of the drawings it will be observed that when the image is floating upon the surface of the water or other 70 liquid, the body will be filled with the liquid to a level coincident with the top or upper edge of the said flange 11 and consequently the image will be supported with its lower portion submerged and its upper portion lying above the surface of the liquid. 75 When pressure is exerted against the opposite sides of the bulb 5 in the manner shown in Fig. 2 of the drawings, the air within the tube 3 above the surface of the liquid therein will be compressed and as a consequence a surplus volume of liquid will be forced upwardly through the opening 10 and into the body 8 of the submergible image. This will cause the image to sink to a greater or 80 less depth in the liquid, depending upon the volume of water entering the image and which volume is, of course, increased in proportion to increase in pressure exerted 85 against the opposite sides of the bulb. When 90 the bulb is relieved of pressure it will again expand and the air compressed within the image will cause an outflow of the surplus volume of the liquid which has entered the same and the image will rise to the surface 95 of the liquid. It will be understood that the flange 11 serves to retain a sufficient volume of liquid within the image to insure of the image maintaining an upright position upon the surface of the liquid when the bulb 100 5 is not under pressure and that this volume remains the same at all times except when the bulb is compressed. Therefore, there is no likelihood of the image becoming so nearly filled with the liquid as to remain submerged after the bulb has been relieved of pressure. It will be further understood that the submergible image may have some form 105

other than that shown in the drawings and that any other type of compression device may be employed in place of the bulb 5.

Having thus described the invention, what is claimed as new is:

A submersible image comprising a hollow body having an inlet opening in its under

side, the body being provided interiorly with a wall surrounding the said opening adapted to retain a predetermined volume of liquid within the said body.

In testimony whereof I affix my signature.

JOHN G. CLEMENS. [L. s.]
